CLAIM

The ornamental design for reversible vest or similar article, substantially as shown and described.

DESCRIPTION

FIG. 1 is a front perspective view of a reversible vest showing my new design;

FIG. 2 is a rear perspective view;

FIG. 3 is a view like FIG. 1 of the vest in reversed condition; and

FIG. 4 is a view like FIG. 2 thereof.

FIG. 1

FIG. 2

FIG. 3

FIG. 4
